UNITED STATES PATENT OFFICE

2,406,724

TOWER FOR DRYING PARACHUTES

Arthur E. Waterman, Fort Atkinson, Wis., assignor to James Manufacturing Company, Fort Atkinson, Wis., a company of Wisconsin

Application August 5, 1943, Serial No. 497,510

8 Claims. (Cl. 135—1)

1

The present invention relates to a tower enclosure adapted for drying parachutes singly or en masse having for its objects generally stated, providing a tower enclosure having a number of rope pulleys at its top suitably spaced and means whereby the top of the parachutes may be attached to one end of a rope and pulled to the top of the tower for drying.

Generally stated the present invention has the following important characteristics: can be manufactured at low cost, is light, storm and weather-proof, collapsible in two or more sections which can be enclosed in bags for stacking, storage or shipping, easily erected or assembled and as easily disassembled and shipped either by truck, 15 trailer or airplane.

An object of my invention is to provide means for escape of air near the top of the tower and means for admitting preferably heated air at its bottom to thereby provide natural circulation of air around the parachutes thus to expedite the drying process.

The above enumerated objects and characteristics provide a device particularly suitable for quick transportation and emergency air corps service.

To these and other useful ends my invention consists of parts, combination of parts or their equivalents and method of manufacture, knocking down, erecting and disassembling as described and claimed and shown in the accompanying drawings in which:

Fig. 1 is an elevational view of my complete tower showing a fraction of another building and having a canopy passageway thereto.

Fig. 2 is a perspective view of the bottom section of my tower when collapsed and packed in a shipping bag.

Fig. 3 is a view of my tower similar to that shown in Figure 1 with part of the roof and wall 40 blankets removed.

Fig. 4 is a bottom view of ring G and all of the parts attached to the ring and above the ring.

Fig. 5 is a top view of the bottom ring of the bottom section of my improved tower. A portion of the collapsible ribs is shown and in section and illustrating four stake rings with which the tower may be secured to the ground.

Fig. 6 is a bottom view of the top section when collapsed for packing or transportation.

Fig. 7 illustrates the preferred form of a floor when viewed from the bottom.

Fig. 8 is a detail of fractional sections through one side of my improved tower.

2

Fig. 9 is a sectional view through a fraction of one side of the bottom section when collapsed.

Fig. 10 is a diagrammatic drawing of my tower building and a fraction of a shelter building as shown in Figure 1.

Fig. 11 is a detail view showing the latch means for holding the parts shown in Fig. 9 in their extended position.

As thus illustrated it will be seen that my improved tower building comprises preferably two sections, the lower section being designated in its entirety by reference character A and the upper section being designated in its entirety by reference character B.

My tower building comprises a number of circular rings which are preferably laminated wood. The bottom ring of the bottom section is designated in its entirety by reference character C. The other rings are designated in their entireties by reference characters D, E, F and G. The floor assembly of my improved tower is designated in its entirety by reference character H.

Floor H comprises spaced slats 10 and spaced slats 11, which are at right angles to slats 10 and preferably considerably further apart than members 10. Members 12 act to suitably secure the ends of certain members 10 together.

Member C has secured thereto in spaced relation a number of spaced stake rings 13 with 30 which the building may be anchored to the ground by means of suitable stakes. I provide a fabric member 14 which on its inner edge is secured to member C, (see Figures 1 and 3). Section A of my improved tower comprises preferably 3 rings 35 C, D and E. These rings are preferably held together in pairs by pairs of ribs 15 of equal length (see Figures 3 and 9), which are hinged at their ends as at 16. These members are arranged in spaced relation as clearly illustrated in Figure 5, their ends being hinged to the rings as at 17. Ring C is adapted to rest on the outer periphery of member H, and may be secured thereto in any suitable manner.

I secure a blanket or fabric covering 18 to members C, D and E (see Figures 1 and 8). Member 45 18 is secured to the rings so it is stretched taut when the ribs are extended as shown in Figures 1 and 3. It will be seen that when the ribs are folded, as in Figure 9, blanket 18 will fold inward as shown in this figure and in Figure 6, and when thus collapsed and folded the units may be placed in a sack 19 and the sack laced as shown in Figure 2 suitable for storing or shipping. The member A shipping package preferably includes unit H.

Blanket 18 is provided preferably with two

openings 20, one on each side, through which warmed air may be forced in order to expedite the drying process. The air passes upwardly through units A and B and escapes through an annular opening in the top of unit B as will hereinafter appear, the air being moved preferably to openings 20 by means of an air heating core and fan.

An opening 21 for attendants (see Figure 10) is provided by extending portions of member 18 outwardly as at 22 so as to form a canopy entrance way. I prefer to position my tower close to the end of a shelter building K and adjacent the door therein, the end of canopy 22 being detachably secured to the frame of the door in member K. Shelter building K is shown and described in a copending application, Serial No. 464,314, filed November 2, 1942, maturing into Patent No. 2,363,916, November 28, 1944.

Member B comprises rings F and G having spaced pairs of ribs 23, their inner ends being hinged together as at 24 and the outer ends being hinged to rings F and G as at 25—25. A blanket 26 is secured to rings F and G as illustrated in Figure 8 and having a length so it will be stretched taut with members 23 extended. An outer ring 27 is secured to ring G by means of spaced blocks 28 so as to provide an annular opening 29 from which the circulating air may escape. A spider frame is secured to member G and comprises a center piece 30 and a number of ribs 31. I provide preferably a ring 32 which is secured to members 31 and has slidably mounted thereon a number of rope pulleys 33 having ropes 34, one end of which is adapted to be tied to the upper end of a parachute, the ropes having suitable lengths for the purpose so the parachutes may be pulled to the top of the tower and the free ends of the ropes anchored at some convenient place on member A. There are generally eight of these pulleys so eight parachutes may be dried at one time if necessary. Pulleys 33 may, however, be suitably anchored to members 31.

I provide a peaked roof comprising a suitably shaped fabric member 40, the lower ends thereof being folded double and being secured to ring 27 as shown in Figure 8. The lower edge extends below this ring as at 41 so as to act as a water drip. It will also be noted that blanket 26 is similarly folded and secured to ring F. The bottom edge extends below ring F and overhangs ring E. I provide a post 42 which rests on a member 30, this post is either hinged at its center so it may be folded similar to ribs 23 or it may be made in one piece as shown and be detachably mounted. Post 42 is preferably provided with a projection 42' and a reinforced opening 43 is provided in the peak of the roof through which member 42' extends forming a suitable support for the peak of the roof. The upper ring E of unit A is preferably cut away on its upper corner as at 44. Member 18 is folded over this cut away portion thus to provide a suitable drip space for member 26. Members E and F are detachably secured together when the building is erected preferably by means of spaced bolts 45 having thumb nuts 46.

It will be seen that unit B may be collapsed by folding the ribs inwardly and removing or folding support 42, member B may be knocked down and placed into a sack similar to that shown in Figure 2. A suitable number of guy ropes 46 are at their upper ends secured to ring F, and after the building has been erected the other ends of these ropes may be staked to the ground so as to form a suitable anchor for the building.

When erecting my tower building ring C is

preferably first secured to member H then the upper half of member A may be extended after which member B may be extended and placed on the top of member A, then the upper portion of the building may be lifted so the low half of member A may be extended. Sometime during this erecting operation member 14 may be moved out of the way or slotted and stakes fitted into rings 13 and driven into the ground so the bottom of the building is suitably anchored to the ground.

It will be understood that my building may be erected or disassembled in any manner suitable for the local conditions. The above described erecting method being the preferred form. After ribs 15 or 23 are extended they are held from collapsing by means of straps 50 (see Figure 11) which are hinged as at 51 on the upper ribs and having an opening 52 adapted to engage bolt 53 in the lower ribs and having a thumb nut 54 by which the strap is made taut when the ribs are extended.

Under some conditions the circulating air will not need to be heated and it may be moved by natural draft and still dry the parachutes successfully.

The building is preferably the right diameter so eight parachutes will hang free in a circle and form a circle large enough so a parachute may be suspended in the center from member 30.

Having thus shown and described my invention I claim:

1. A collapsible tower building of the class described, comprising a plurality of spaced rings, a number of spaced ribs forming a connection between adjacent rings, said ribs comprising two pieces of equal length and being hinged together at their centers and hingedly secured at their other ends to the rings, and means whereby the ribs are foldable inwardly whereby the rings may be moved adjacent each other, a blanket secured at its ends to said rings forming the walls of the building, and adapted to be stretched taut when the ribs are extended and whereby the blanket may fold between the rings when the ribs are folded.

2. A device as recited in claim 1 including, a frame secured to the top ring and a peaked roof formed of fabric material, the edges thereof being secure to the top ring, a detachable post supported by said frame at the center thereof and forming a support for the peak of said roof, whereby said roof may collapse when said post is removed.

3. A collapsible tower building of the class described, comprising a plurality of vertically spaced rings, a number of spaced ribs forming connection between adjacent rings having hinges midway their ends, the other ends of the ribs being hinged to the rings, and means whereby the ribs may be folded inwardly whereby the rings may be moved adjacent each other, a blanket forming an outer wall secured at its ends to the rings and adapted to be made taut when the ribs are moved into their extended position and whereby when the ribs are folded the blanket may be folded inwardly and between the ribs.

4. A collapsible tower building of the class described, comprising three vertically spaced rings, a number of spaced ribs forming connections between adjacent rings, the ribs being arranged in pairs of equal length and hinged together at their inner ends, the outer ends of said ribs being hinged to their adjacent rings and having means whereby the ribs may be folded inwardly and the rings moved adjacent each other, a blanket form-

ing an outer wall secured at its ends to the two outer rings and midway its ends to the center ring, whereby the blanket will be made taut when the ribs are moved to their extended position and whereby when the ribs are folded the blanket may be folded inwardly and between the ribs.

5. A collapsible device as recited in claim 4 including, another building member comprising two spaced rings and a number of spaced ribs forming a connection therebetween, said ribs comprising two pieces of equal length and being hinged together at their adjacent ends and being hinged to the adjacent rings and having means whereby the ribs may be folded inwardly, a blanket secured at its ends to said rings and adapted to be stretched taut when the rings are extended and whereby the blanket may fold inwardly between the ribs when the ribs are folded, a frame member secured to the top rim and a peaked roof formed of fabric material, the outer edges being secured to the top ring, a detachable post adapted to rest on said frame at the center thereof and act as a support for the peak of said roof, said last building member adapted to rest on the top of the first building member, and means for detachably securing adjacent rings together.

6. A device as recited in claim 4 including, a circular floor member having a diameter substantially equal to the outside diameter of the bottom ring of said bottom unit and being adapted to be detachably secured to the ring.

7. A tower building of the character described, comprising a lower section and an upper section and a roof section, the lower and upper sections comprising a number of rings having therebetween a number of spaced ribs forming connections between adjacent rings, said ribs being arranged in pairs of equal length and hinged together at their inner ends, the outer ends of the pairs of ribs being hinged to their adjacent rings,

whereby the ribs may be folded inwardly and the rings moved adjacent each other, blankets forming an outer wall for said lower and upper sections and being secured at their ends to their respective rings whereby the blankets will be made taut when the ribs are moved to their extended position and whereby when the ribs are folded the blankets may be folded inwardly between the ribs, said lower and upper sections being detachably secured together, said roof section comprising a peaked roof having a ring at its bottom and having a larger diameter than the upper ring of said upper section and being secured thereto to thereby provide an annular downdraft air outlet and a water shed for the top of the building.

8. A collapsible tower building of the character described comprising; a plurality of vertically spaced rings, a number of circumferentially spaced ribs forming connections between adjacent rings having hinges mid-way their ends, the other ends of said ribs being hinged to the rings, and means whereby the ribs may be folded inwardly whereby the rings may be moved adjacent each other, a blanket forming an outer wall secured at its ends to the rings and adapted to be made taut when the ribs are moved into their extended position and whereby when the ribs are folded the blanket may be folded inwardly and between the ribs, an ingress opening in said blanket at the bottom thereof, another building in close proximity to the first building, and having an opening which registers with said first opening, a canopy surrounding said first opening and being secured thereto and adapted to be detachably secured to said other building around the other building opening, a frame secured to the top ring, and a canvas covering for the building adapted to be supported by the top ring and its frame.

ARTHUR E. WATERMAN.
